UNITED STATES PATENT OFFICE.

ELMO HUGH CALLEN, OF LEECHBURG, PENNSYLVANIA.

CURTAIN-POLE AND SHADE-FIXTURE.

SPECIFICATION forming part of Letters Patent No. 710,352, dated September 30, 1902.

Application filed February 11, 1902. Serial No. 93,551. (No model.)

To all whom it may concern:

Be it known that I, ELMO HUGH CALLEN, a citizen of the United States, residing at Leechburg, in the county of Armstrong and State 5 of Pennsylvania, have invented a new and useful Improvement in Curtain-Poles and Shade-Fixtures, of which improvement the following is a specification.

This invention relates to certain new and 10 useful improvements in curtain-poles and shade-fixtures, and relates more particularly to that class of curtain-poles wherein the use of pins and rings is entirely dispensed with.

The present invention has for its object to 15 provide adjustable brackets for shade-fixtures that may be adjusted to receive any width of shades; furthermore, to provide a curtain-pole wherein the curtain may be easily attached, draped in an artistic manner, and 20 readily removed therefrom when desired.

With the above and other objects in view the invention consists in the novel combination and arrangement of parts to be herein-after more fully described, and specifically 25 pointed out in the claim.

In describing the invention in detail reference is had to the accompanying drawings, forming a part of this specification, and wherein like numerals of reference indicate 30 like parts throughout both views, in which—

Figure 1 is a perspective view of my improved curtain-pole and shade-fixture. Fig. 2 is an enlarged side elevation thereof.

In the drawings the reference-numeral 1 35 indicates the brackets, carrying rings 2, in which the pole 3 is slidably secured, said rings being provided with set-screws 4.

The reference-numeral 5 represents rings slidably mounted upon the pole 3, having set-

screws 6 and a lower extension 7, said extension having formed therein a square opening 8 in one of the rings and a round opening 9 in the other to receive the shade-roller 10, carrying the window-shade 11, the latter being constructed in the ordinary manner. To one 45 end of the pole 3 is secured an arm 12, carrying a rod 14, and to the other end of said pole is secured a bracket 15, carrying a rack 16, in which is secured the end of the rod 14. The curtain 17 is secured and draped over the 50 rod 14.

The many advantages obtained by the use of my improved device will be readily apparent from the foregoing description, taken in connection with the accompanying drawings. 55

It will be noted that various changes may be made in the details of construction without departing from the general spirit of my invention.

Having fully described my invention, what 60 I claim as new, and desire to secure by Letters Patent, is—

In a combined curtain-pole and shade-fixture comprising a pole 3 having mounted thereon adjustable shade-brackets, an arm 65 carrying a rod secured to one end of the pole, and a bracket carrying a rack secured to the other end of the pole, the latter being adapted to receive the end of said rod, all parts being arranged substantially as shown and described. 70

In testimony whereof I have hereunto signed my name in the presence of two subscribing witnesses.

ELMO HUGH CALLEN.

In presence of—

J. O. STUART,
R. M. CLINE.
